[57] ABSTRACT

The present invention relates generally to knitting machines which incorporate electrically operated knitting needles of the double hook latch type which have no butts and wherein the machine itself has no cams. Electromagnetic energizers are employed to reciprocate the buttless knitting needles by including longitudinally spaced coils which are activated in accordance with a predetermined sequence of operation to reciprocate the needle to form a predetermined knitted pattern configuration. The machine also includes a vacuum take-up device to control heat flow through the apparatus so that the heat which is developed when the coils are activated may be utilized for heat setting of the newly knitted fabric.

KNITTING MACHINE

BACKGROUND OF THE INVENTION

The present invention relates generally to the knitting machine art, and more particularly, is directed to improvement in circular knitting machines.

Knitting machines have long been developed which employ a plurality of latch type needles which operate in conjunction with wool or other fiber yarn for purposes of knitting fabrics. The use of circular knitting machines to knit a tubular fabric have become increasingly popular and today are of considerable importance in the industry. The prior art circular knitting machines include a plurality of circularly arranged knitting needles which are controlled in accordance with well known knitting principles to perform predetermined knitting stitches to produce a knitted fabric.

The knitting needles which are most popularly employed at the present time are of the so called latch type needles wherein a latch is pivoted relative to the body of the needle in predetermined manner by the yarn to form new stitches and to cast off old stitches for the desired knitting operations. Most prior art knitting needles are of the single latch type, although compound latch needles are already known and have been employed for specialized knitting tasks.

All prior art knitting needles of which I am familiar employ butts which project from the shank of the needle and ride within cams incorporated in the machine design to move the latch end of the needle forwardly and rear-wardly of the yarn in predetermined sequential manner to form new stitches and to cast off old stitches as required to knit the desired pattern. I am aware of double hook knitting needles of the type having latch type hooks at each end which are employed in conjunction with flat bed knitting machines as disclosed in U.S. Pat. No. 3,451,229. I am also aware of knitting machines which employ the use of electromagnetic forces in carrying out certain knitting operations. For example, in U.S. Pat. No. 3,426,550, electromagnetic selectors are provided for shifting the needle butts between a pair of cam tracks during the knitting operation for performing predetermined knitting stitches.

All of the prior knitting machines are subject to considerable loss of production time which is caused by breakage of the needle butts during knitting operations. Additionally, mishaps in camming are also frequent causes of down-time in existing equipment. The use of cams in presently available knitting machines of the circular type causes a definite limitation in the number of feeds which can be employed about the circumference of the machine. For example, most existing circular knitting machines employ a maximum of 96 feeds due to space limitations. By limiting the number of feeds which may be employed with a knitting machine, the rate of production of that machine is similarly limited. As knitting progresses, each feed knits a certain additional length to the fabric. For example, one feed is capable of knitting approximately one-one hundredths of an inch to the fabric. Accordingly, if there are 30 feeds, each revolution of the machine will result in knitting thirty one-hundredths of an inch. Thus, should 96 feeds be employed, each revolution of the machine would result in an additional length of ninety-six one-hundredths of an inch. In the event that a machine could be developed which was capable of accommodating additional feeds, each revolution of the circular

machine would result in increased fabric production at a rate that was directly proportional to the number of feeds employed.

SUMMARY OF THE INVENTION

The present invention relates generally to knitting machines which employ knitting needles of the latch type and more particularly, is directed a camless knitting machine which is capable of producing all of the usual knitting stitches and which employs latch type needles having no butts whatsoever.

In accordance with the present invention, a plurality of magnetic energizers concentrically position about the needle bed of a circular knitting machine. A plurality of contacts space about a switch ring which is rotatively driven about the magnetic energizers to alternately energize and de-energize the magnetic energizers which are stationarily positioned on the needle bed. Each magnetic energizer includes a plurality of coils which, when activated is pre-programmed sequence, act to urge the needle reciprocally within the magnetic energizers. In the case of purl stitches, two magnetic energizers arrange in end to end relationship and a single needle of the double hook type can be propelled back and forth between the magnetic energizers.

The alternate powering and de-energizing of the plurality of coils of the magnetic energizers sets up limited magnetic fields for short periods of time to alternately reciprocate a plurality of compound knitting needles in response to the control operation of a plurality of programming switches. The needles are specially constructed of the double hook type having a latch type hook at each end for knitting purposes. The knitting needles are fabricated of magnetically attractive material such as steel and in a modified embodiment, may be treated to impress permanent magnetic qualities in the knitting needle construction.

By employing magnetically attractive knitting needles and magnetic energizers to reciprocate the knitting needles, all butts and cams previously required in conventional knitting apparatus can be completely eliminated. Additionally, the maximum number of feeds about the periphery of the needle bed can be greatly increased due to the simplified mechanism.

By employing a great number of magnetic energizers, quantities of electrically generated heat from the energizer coils will be available in the vicinity of the newly knitted fabric. A vacuum take-up has been employed to control the build up of heat and to direct the heated air in a manner to permit close control of temperatures through the knitted fabric to utilize the electrically generated heat for heat setting of the knitted fabric as the fabric is produced on the machine.

It is therefore an object of the present invention to provide an improved knitting machine of the type set forth.

It is another object of the present invention to provide an improved knitting machine which is completely camless in operation.

It is another object of the present invention to provide a novel knitting machine that employs a plurality of knitting needles, the said needles being fabricated of magnetically attractive material.

It is another object of the present invention to provide a novel knitting machine which employs magnetically attractive needles having no butts whatsoever.

It is another object of the present invention to provide a novel knitting machine which is capable of greatly increased production speeds.

It is another object of the present invention to provide a novel knitting machine that employs magnetic energizers and magnetically attractive needles reciprocal within the energizers, said magnetically attractive needles being capable of performing all knitting stitches which were heretofore knitted when using conventional equipment.

It is another object of the present invention to provide a novel knitting machine that is rugged in construction, that incorporates fewer moving parts and that is trouble-free when in operation.

Other objects and a fuller understanding of the invention will be had by referring to the following description and claims of a preferred embodiment thereof, taken in conjunction with the accompanying drawings, wherein like reference characters refer to similar parts throughout the several views and in which:

BRIEF DESCRIPTION OF THE DRAWINGS

FIG. 1 is a front perspective view of a circular knitting machine constructed in accordance with the teachings of the present invention.

FIG. 2 is a cross sectional view taken along Line 2—2 of FIG. 1, looking in the direction of the arrows.

FIG. 3 is a cross sectional view taken along Line 3—3 of FIG. 1, looking in the direction of the arrows.

FIG. 4 is an enlarged, side elevational view of a compound latch needle fabricated in accordance with the present invention.

FIG. 5 is a schematic electrical wiring diagram for operation of the electrical magnetic energizers.

FIG. 6 is a schematic diagram showing the interaction of the magnetic energizer, the compound-latch needle and schematic circuit wiring controlling the function of a magnetic energizer.

FIG. 7 is a view similar to FIG. 6 showing operation of the device in cast off position when knitting a plain knit fabric.

FIG. 8 is a view similar to FIG. 7 showing the position of parts when the old stitch is still on the latch and when the needle is ready to receive a new yarn.

FIG. 9 is a view similar to FIG. 8 showing the arrangement of parts when the old stitch is below the latch and the new yarn is in the hook immediately before dropping off the old stitch.

FIG. 10 is a schematic view showing the arrangement of parts for purl stitches wherein the needle will be moved across from one needle bed into the opposite needle bed.

FIG. 11 is a view similar to FIG. 10 showing the arrangement of parts to form purl stitches with the needle still in movement across the two needle beds.

FIG. 12 is a view similar to FIG. 11 showing the arrangement of parts when the needle has reached the position to finally form the purl stitch.

FIG. 13 is a partial side elevational view of the vacuum heat take-up device, showing an enlarged representation of the area designated in FIG. 2.

FIG. 14 is a cross sectional view taken along Line 14—14 of FIG. 13, looking in the direction of the arrows.

FIG. 15 is a schematic representation of the needle bed and energizer wiring, showing an enlarged representation of the area designated in FIG. 2.

FIG. 16 is an enlarged portion of the fabric as knitted by the present apparatus.

FIG. 17 is an enlarged, partial, top plan view of a portion of the stitch pattern control tape.

FIG. 18 is a schematic, side elevational view of the tape of FIG. 17 in use.

FIG. 19 is a schematic wiring diagram of the apparatus controlled by the tape of FIG. 17.

DESCRIPTION OF THE PREFERRED EMBODIMENTS OF THE INVENTION

Although specific terms are used in the following description for the sake of clarity, these terms are intended to refer only to the particular structure of my invention selected for illustration in the drawings and are not intended to define or limit the scope of the invention.

Referring now to the drawings, I show in FIG. 1 a circular knitting machine generally designated 10 wherein 20 a plurality of yarn spools 12 feed yarn 14 upwardly through the tensioning arms 16. The yarn then feeds upwardly through the stop motion 18 and then internally downwardly towards the rotating yarn and second cylinder platform 20. In the embodiment illustrated, 25 the needle bed 22 comprises a plurality of concentrically positioned magnetic energizers and compound latch needles which are operative therein as hereinafter more fully set forth.

Referring now to FIGS. 2 and 3, the needle bed 22 is shown comprising a plurality of pairs of magnetic energizers 24, 26 which are stationarily affixed in position. A plurality of switch contacts 28, 30 rotatively mount on the machine frame 32 and are rotatively driven about the magnetic energizers by the main drive 34 through a shaft and gear arrangement 36 in any well known manner. It will be appreciated that there will be one armature for each yarn feed 38 and these armatures will rotate in the usual manner. The yarns and contacts are synchronized so that a feed positions in alignment with an energizer when the contact closes the switch for each individual needle to thereby energize the needle to emerge from its associated magnetic energizer 24 or 26 to engage the yarn 38 for knitting purposes as hereinafter more fully set forth. A plurality of vacuum take-up heads 40 mount beneath the needle bed 22 and position adjacent the knitted fabric 42 for heat setting purposes as hereinafter more fully set forth. A plurality of patterning switching devices are provided for each energizer 24, 26 for interaction with a pattern switch controller in the manner hereinafter more fully discussed.

Referring now to FIG. 4, I show a compound latch needle 48 which is reciprocal within each magnetic energizer 24, 26 in response to electrical energy supplied through the switch contacts 28, 30 and the patterning switching devices. Each compound latch needle 48 comprises a body 50 which is composed of magnetically active material such as hardened steel and terminates at either end in a conventional hook 52, 54 for receiving new stitches as hereinafter more fully set forth.

Each hook 52, 54 has a pivotal latch 56, 58 associated with it and the hook and latch assemblies 52, 56 and 54, 58 function to pull on new stitches and to cast off old stitches in conventional manner during the knitting procedures. Preferably, the latches are fabricated of strong, non-magnetic material, such as suitable plas-

tic. The compound latch needles 48 function horizontally between horizontally disposed magnetic energizers to equalize the forces of gravity throughout the operation so that equal forces will be applied to reciprocate the needle during all portions of the knitting cycle. Additionally, by horizontally disposing both the needles 48 and the magnetic energizers 24, 26, there is no possibility of a needle dropping out by gravity when the machine 10 is shut down after the completion of a knitting operation.

A schematic electrical wiring diagram is set forth in FIG. 5 wherein ordinary 220 volt alternating current is impressed upon the primary winding 60 of a step-up transformer 62. The secondary winding 64 transforms the current to 440 volts and feeds the higher voltage current to a rectifier 66 which incorporates a plurality of diodes 68, 70, 72, 74. The diodes act conventionally to convert the alternating current to 440 volt direct current to operate the plurality of magnetic energizer coils as hereinafter more fully discussed. The rectifier leads 76, 78 carry the 440 volt direct current to the magnetic energizers 24, 26 for reciprocation of the compound latch needles 48 as hereinafter more fully set forth.

Referring now to FIG. 6, I show a three position magnetic energizer 80 which is fabricated of non-magnetic, sturdy material such as a suitable plastic and includes a hollow, generally rectangular interior space 82 of size to receive a compound latch needle 48 therewithin and to permit relative reciprocal motion of the needle with respect to the magnetic energizer 80. The control end 84 of the energizer 80 is interiorly threaded or otherwise treated to adjustably receive the adjusting plug 86 therewithin. The adjusting plug 86 inwardly carries a resilient section 88, which terminates inwardly and carries the hard rubber bumper 90. The rubber bumper resiliently mounts on the section 88 and serves as the inward limit of travel for the needle 48 during operation of the device. Accordingly, by adjusting the adjustable plug 86 relative to the control end 84, such as by turning the screw thread 92, the rubber bumper 90 may be positioned nearer or further from the open end 94 of the energizer 80 to thereby provide a convenient method for adjusting the length of stroke of the needle 48 as it is propelled to thereby control the size of the stitch as the needle is reciprocated by the energizer coils.

A plurality of coils 96, 98, 100 encircle each energizer in spaced relationship over the rectangular interior space 82 and develop magnetic fields in the coil areas in accordance with well known principles of electro-magnetic construction for magnetic attraction of the needle 48. An electrical circuit 102 has its leads 104, 106 connected to the rectified leads 76, 78 in well known manner. An action switch 108 controls the flow of current to the coils 96, 98, 100 through the electrical circuit 102 in response to closing of the switch by the revolving switch contacts 28 or 30. Thus, each magnetic energizer can only function to reciprocate its associated latch needle 48 when the switch contacts 28 or 30 close a respective action switch 108. The coils 96, 98, 100 connect in parallel with the circuit 102 and accordingly, can be activated only when the switch 108 is closed by a switch contact. When the switch 108 is open, no current can flow through the circuit 102 and the coils 96, 98, 100 will be completely inactive. Each coil 96, 98, 100 is controlled by an associated pattern-

ing switch 110, 112, 114 and these patterning switches are in turn regulated by operation of the pattern controller as hereinafter more fully set forth. Thus, the switches 110, 112, 114 may be activated only when the action switch 108 is closed as controlled by the revolving switch contact 28, 30 and when operated by function of the pattern controller.

Referring now to FIG. 7, I show a schematic arrangement wherein the needle 48 is urged to its innermost position within the interior space 82 by energization of the innermost coil 96 through closing of the switch 110 as determined by the patterning controller (not shown). With the coil 96 activated, the innermost hook 52 bottoms against the rubber bumper 90 which had previously been adjusted to the predetermined desired location relative to the interior space 82 of the magnetic energizer. The latch 58 is shown in the cast-off position wherein the old loop is cast off and drops over the closed latch and the new yarn thus forms a new stitch in accordance with well known knitting principles. The rubber bumper 90 is provided of adjustable, resilient construction to absorb the momentum of the needle and to prevent bounce.

In FIG. 8, I show the magnetic energizer 80 with the center coil 98 energized by closing of the switch 112 after closing the switch 108. Kindly note that the other two patterning switches 110, 114 are open to thereby de-energize their associated coils 96, 100. Energization of the coil 98 moves the needle 48 outwardly relative to the magnetic energizer 80 into position with the latch open to retain the old stitch so that the stitch will not be cast off when the needle moves inwardly relative to the magnetic energizer 80. The hook 54 is open to receive the new yarn and thus, when the new yarn is fed in on this feed, it will form a tubked stitch.

As illustrated in FIG. 9, when the switch 114 closes in response to the patterning controller, the coil 100 is energized to urge the needle 48 outwardly to its outermost position relative to the magnetic energizer 80. In this position, the needle 48 moves outwardly of the interior space 82 a sufficient distance to have the old stitch (not shown) fall off of the latch so that when the needle moves backwardly toward the rubber bumper 90, the old stitch will close the latch and drop off of the needle. In this operation, the new yarn, which has been fed into the open hook 54 of the needle will form into a new stitch. The three needle positions illustrated in FIGS. 7, 8 and 9 enable the machine to be employed for plain knitting purposes.

Referring now to FIG. 10, I show a pair of magnetic energizers 24, 26 which are each constructed similarly to the three position magnetic energizer 80. The magnetic energizers 24, 26 are shown in horizontal, longitudinally juxtaposed relationship wherein the needle 48 may be moved from one needle bed to the other to form a purl stitch 128. Each magnetic energizer 24, 26 includes a hollow rectangular interior space 82, an adjustable plug 86, a resilient section 88 and a rubber bumper 90 which are constructed in the manner hereinbefore described. Additionally, each magnetic energizer 24, 26 is similarly equipped with a plurality of three longitudinally spaced coils 96, 98, 100, which are in turn controlled by their respective patterning switches 110, 112, 114 in the manner hereinbefore described. Each magnetic energizer 24, 26 is powered by an electrical circuit 102, the action of which is controlled by a series connected action switch 108. In the

position of FIG. 10, the left magnetic energizer 24 middle coil 98 is energized by closing of the patterning switch 112 to urge the needle 48 outwardly relative to the interior space 82 in the manner hereinbefore described in the arrangement of FIG. 8. At the same time, the outermost coil 100 of the right magnetic energizer 26 is energized by closing of the switch 114. The magnetic energizers 24, 26 are arranged in horizontal axial alignment and are spaced apart a distance sufficient to permit transfer of the needle 48 from the interior space 82 of the left magnetic energizer 24 to the interior space 82 of the right magnetic energizer 26. Thus, when the needle 48 moves into the right needle bed as represented by the magnetic energizer 26, the old stitch will be cast off of the latch 58 and the new yarn will be pulled onto the reverse side to form a purl stitch. The old stitch will move back and close the latch 56 on the opposite side of the compound needle. When the new yarn 130 is pulled into the opposite side of the needle, a purl stitch 128 will be formed.

In FIG. 11, the needle 48 is still in movement across the two needle beds between the magnetic energizer 24 and the magnetic energizer 26 to form the purl stitch 128. As the needle moves into the interior space 82 of the energizer 26, the formed stitch and the new yarn 130 causes the latch 56 to close and the stitch will then be cast off of the left end of the needle 48 when it is in the cast-off position within the magnetic energizer 26. It will be observed that as the needle 48 passes between the left magnetic energizer 24 and the right magnetic energizer 26, the coil 100 is energized by closing of the switch 114 to urge the needle outwardly of the interior space 82 of the energizer 24. Simultaneously, the middle coil 98 of the right magnetic energizer 24 is activated by closing the switch 112 to attract the hook end 54 of the needle 48 into the interior space 82 of the right magnetic energizer 24.

As seen in FIG. 12, the needle 48 reaches its final position within the interior space 82 of the magnetic energizer 26 to finally form the purl stitch 128. In this position, the switches 110, 112, 114 of the magnetic energizer 24 are open to de-energize the coils 96, 98, 100 which therefore have no magnetic attraction whatsoever for the needle 48. The switch 110 closes to energize the rearwardmost coil 96 of the right magnetic energizer 26 to pull the needle 48 to its rearwardmost position by means of magnetic attraction. In this position, the latch 56 closes upon the hook 52 to permit the stitch 128 to be cast off as the needle fully seats within the interior space 82. It will be appreciated that the coils 96, 98, 100 of each pair of the axially aligned, spaced energizers 24, 26 may be operated in sequence as hereinbefore illustrated to reciprocate the needle 48 backwardly and forwardly within the interior space 82 of the magnetic energizers 24, 26 to continuously knit purl stitches.

Referring now to FIG. 13 and 14, I show a vacuum take-up head 116 which is positioned to pull ambient air from on top of the needle bed through the knitted fabric 42. The coils 96, 98, 100 electrically generate heat above the needle bed and this heated air can be utilized to heat set the fabric as it is knitted by the machine 10. The face 118 of the vacuum take-up head 116 inclines at an angle of approximately 30° from the vertical to pull air from the needle bed above and is drilled or otherwise treated to provide a plurality of openings 120 to receive the air from the vicinity of the

needle bed. The head 116 is formed to provide a hollow interior passage 122 which is in communication with the plurality of openings 120. An exit passage 124 connects to the interior 122 of the vacuum take-up head 116 and leads to a connection to a vacuum pump (not shown) of suitable design and capacity in any well known manner. The heated air which enters the take-up head 116 is preferably pulled directly through the fabric 42 prior to entering the holes 120. This may be accomplished readily by placing the vacuum take-up head relative to the location of the knitted fabric in position to draw air through the knitted fabric from the needle bed. It will be appreciated that considerable heat will be generated by the plurality of coils 96, 98, 100 of the magnetic energizers 24, 26 and it is this heat that is utilized in heat setting of the fabric. The temperature of the heated air passing through the fabric 42 may be regulated by varying the amount of air entering the vacuum take-up head 116. The volume of air may readily be regulated in well known manner such as by employing dampers 126 mounted in the exit passage 124, by providing volume dampers (not shown) across the face 118 of the take-up head or by varying the operation of the vacuum pump (not shown), all in well known manner by those skilled in the air handling art.

As best seen in FIGS. 2 and 15, the outer switch contacts 28 mount upon the outer switch ring 132 and the inner switch contacts 30 mount upon the inner switch ring 134 to revolve about a shaft and gear system 36 in conventional manner to rotate the outer switch ring 132 and the affixed outer switch contacts 28 at uniform rotative speed. Through suitable belt and pulley system 172, 174, 176, 178, 180 the inner switch ring 134 is simultaneously rotated by the motor 34 in synchronism with the outer switch ring 132 to that the outer switch contacts 28 rotate at precisely the same speed as the inner switch contacts 30. Also, the respective contacts 28, 30 are peripherally spaced about their respective associated rings to rotatively in turn close the respective action switches 108 of longitudinally juxtaposed, axially aligned pairs of magnetic energizers 24, 26. In the embodiment illustrated, the contacts 28, 30 each include a shaped section 138 which is rotated into contact with the points 140, 142 of each switch 108 to momentarily close the switch to thereby energize the electrical circuit 102 to function the magnetic energizers 24, 26. The armatures 144 respectively extend from the contacts 30 and are rotated therewith upon rotation of the inner switch ring 134. Each armature 144 rotates a yarn 14 into position between the longitudinally spaced magnetic energizers 24, 26 when the contacts 28, 30 close the respective action switches 108. In this manner, the yarn feed is automatically positioned for take up by the needle 48 for knitting purposes when the needle is propelled by its associated energizer or energizers.

In order to control the operation of the patterning switches 110, 112, 114, it is contemplated that the movement of the needle 48 will be controlled by the usual film type card controller as presently in use. In the case of plain or jersey knits, the card need have only three positions to carry out the sequence of knitting steps as set forth in FIGS. 7 - 9. In the case of purl stitches, the pattern controller (not shown) will have six contacts, one controlling each of the switches 110, 112, 114 of the magnetic energizers 24, 26 to carry out the sequence of operations as set forth in FIGS. 10 -

12. In lieu of employing a pattern controller of conventional design, an electronic scanner of the type marketed under the trademark "Chroma-Scan" by Scientific Technology, Ltd., Rehovot, Israel could also be employed. This device is based on the principle of providing fully automatic preparation of cards, tapes or disks directly from the designer's sketch to any make of jacquard knitting machine. The electronic scanner scans the drawing and automatically senses the color of each point in the drawing and employs a plug-in programming module compatible for use with existing card controlled machines. The module performs all the commutation and control functions needed to convert the designer's drawing to the jacquard code of the machine and is suitable on any six feed knitting sequence. By functioning to open and close the patterning switches 110, 112, 114 in programmed sequence, the electronic scanner in conjunction with the switch contacts 28, 30, which act to sequentially close the various action switches 108, serves to provide a fully automated, camless and buttless knitting operation.

As illustrated in FIG. 16, the device of the present invention can be employed to knit a fabric 42 of conventional purl stitches wherein 146 represents the top of the new stitch, 148 represents the top of the old stitch and 150 illustrates the new stitch.

Referring now to FIGS. 17, 18 and 19, I show a novel patterning mechanism which may conveniently be employed in conjunction with the present apparatus. A film 154 runs between a supply spool 162 and a take-up spool 164 in conventional manner and is provided with a plurality of longitudinally aligned openings 156, 158, 160 for patterning stitch control purposes. For straight knitting as in FIGS. 7, 8 and 9, only three coils 96, 98, 100 needs be controlled and so the tape need only three longitudinally aligned rows of openings as illustrated. In the case of purl stitches as in FIGS. 10, 11 and 12, the tape 154 must control six patterning switches and so six aligned rows (not shown) would have to be provided. In operation, each patterning coil switch 110, 112, 114 could be equipped with a movable blade 166 which would normally be retained in the switch open position by the material of the pattern film 154. The movable blades 166 would be aligned to register over a respective row of longitudinally aligned openings 156, 158 or 160. When the tape is driven by the spools 162, 164 into longitudinal position wherein a blade 166 registered with an opening, the opening 156, 158 or 160 then allows the movable blade 166 to bias to its switch closed position 168 to thereby energize its respective associated coil 96, 98 or 100 for needle reciprocation in the manner hereinbefore described.

Although I have described the present invention with reference to particular embodiments therein set forth, it is understood that the present disclosure has been made only by way of example and that numerous changes in the details of construction may be resorted to without departing from the spirit and scope of the invention. Thus, the scope of the invention should not be limited by the foregoing specification but rather only by the scope of the claims appended hereto.

I claim:

1. In a knitting machine of the camless type and having a needle bed, the combination of
  - A. a plurality of magnetic energizers positioned upon the needle bed,

1. said magnetic energizers being fabricated of non-magnetic material to an elongate configuration,
2. said magnetic energizers each defining an interior space having a first open end and a second closed end,
3. said magnetic energizers each having a plurality of longitudinally spaced coils responsive to the flow of electrical current;
4. a latch type knitting needle reciprocal within the magnetic energizer and having two ends,
  1. said needle being fabricated of magnetically attractive material,
  2. said needle being moved relative to the magnetic energizer by the activation of coils; and
5. electrical control means to control the flow of electrical current to the coils.
6. The invention of claim 1 wherein the needle is equipped with a hook and a latch at each end.
7. The invention of claim 2 wherein the needle has no butts.
8. The invention of claim 3 wherein the second closed end of the magnetic energizer is provided with resilient means to determine the innermost distance of travel of the needle within the interior space.
9. The invention of claim 4 wherein the position of the resilient means is adjustable relative to the interior space to vary the size of stitches knitted by the needle as it is reciprocated.
10. The invention of claim 1 wherein the electrical control means include an electrical circuit magnetic energizer and a switch to control the flow of electricity to each electrical circuit, said switch having an open position and a closed position.
11. The invention of claim 6 and a contact ring mounted on the knitting machine and having contacts affixed thereon, said contact ring being rotated to close each said switch momentarily to energize the electrical circuit.
12. The invention of claim 7 wherein each coil is energized by the electrical circuit through a patterning switch, said patterning switches having open and closed positions.
13. The invention of claim 8 and means to function the patterning switches in pre-programmed sequence.
14. The invention of claim 9 wherein the means to function the patterning switches include an elongate web, said web being pierced to provide a plurality of openings, the said web being driven to pass the openings across the patterning switches.
15. The invention of claim 10 wherein the patterning switches are functioned by the said openings, each said patterning switch being closed when the openings are driven past the patterning switch.
16. The invention of claim 1 wherein pairs of magnetic energizers are arranged in axially aligned, longitudinally justaposed position.
17. The invention of claim 12 wherein the open ends of each magnetic energizer in a pair face each other.
18. The invention of claim 13 wherein the pairs of magnetic energizers radially position upon the needle bed.
19. The invention of claim 14 wherein a single needle is associated with each said pair of magnetic energizers.
20. The invention of claim 15 wherein pre-programmed activation of the longitudinally spaced coils of each magnetic energizer of each said pair

11

causes the needle to reciprocate between the interior spaces of each magnetic energizer of a pair for knitting purposes.

17. The invention of claim 1 and air take-up means positioned below the needle bed, said air take-up means controlling air flow through the knitting machine so that heat generated by the coils may be used for heat setting the newly knitted fabric.

18. The invention of claim 17 wherein the air take-up means include a duct and vacuum means to pull air into

5 10

12

the duct, said knitted fabric being positioned between the magnetic energizers and the intake to the duct so that heated air passes through the knitted fabric prior to entering the duct.

19. The invention of claim 18 wherein the duct is provided with volume control means to regulate the flow of heated air.

20. The invention of claim 1 wherein the magnetic energizers are horizontally aligned.
